(57) **CLAIM**

The ornamental design for a pill case, as shown and described.

DESCRIPTION

FIG. 1 is a front perspective view of the pill case showing our new design;

FIG. 2 is a front view of the pill case of the new design;

FIG. 3 is a rear view of the pill case of the new design;

FIG. 4 is a left side view of the pill case of the new design;

FIG. 5 is a right side view of the pill case of the new design;

FIG. 6 is a top view of the pill case of the new design;

FIG. 7 is a bottom view of the pill case of the new design; and,

FIG. 8 is a front perspective view of the pill case of the new design showing the operational function of one of the covers for each pill reservoir.

The pill case details shown in dashed lines illustrate portions of the pill case that form no part of the claimed design.
